(57) **CLAIM**

The ornamental design for cockpit module for a vehicle, as shown and described.

DESCRIPTION

FIG. 1 describes overall shape of the design.

FIG. 2 describes front view of the design.

FIG. 3 describes rear view of the design.

FIG. 4 describes left side view of the design.

FIG. 5 describes right side view of the design.

FIG. 6 describes top view of the design; and,

FIG. 7 describes bottom view of the design.

The broken lines in FIG. 3 illustrate portions of the cockpit module for a vehicle that form no part of the claimed design.

1 Claim, 5 Drawing Sheets
